US00D885173S

(12) **United States Design Patent** (10) Patent No.: **US D885,173 S**
(45) Date of Patent: **** May 26, 2020**

(54) **CLAMP**

(71) Applicant: **TKO Clamping Systems, LLC**,

Pocatello, ID (US)

(72) Inventors: **Timothy L. Magagna**, Pocatello, ID (US); **Stanford L. Caldwell**, Pocatello, ID (US); **Shea S. Caldwell**, Pocatello, ID (US); **Kary R. Christopherson**, Ridgefield, WA (US); **Craig L. Sandstrom**, Pocatello, ID (US)

(73) Assignee: **TKO Clamping Systems, LLC**, Pocatello, ID (US)

(**) Term: **15 Years**

(21) Appl. No.: **29/653,158**

(22) Filed: **Jun. 13, 2018**

(51) LOC (12) Cl. **08-08**

(52) U.S. Cl.

USPC **D8/396**

(58) **Field of Classification Search**

USPC D8/394-396, 349-356, 373, 400, 21-26,

D8/29, 499

(57) **CLAIM**

The ornamental design for a clamp, as shown and described.

DESCRIPTION

FIG. 1 is a front perspective view of a clamp in accordance with a first embodiment of the present claimed design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is an exploded front perspective view thereof;

FIG. 10 is a perspective view thereof shown in an unclaimed environment of use;

FIG. 11 is a front perspective view of a clamp in accordance with a second embodiment of the present claimed design;

FIG. 12 is a rear perspective view thereof;

FIG. 13 is a left side view thereof;

FIG. 14 is a right side view thereof;

FIG. 15 is a front view thereof;

FIG. 16 is a rear view thereof;

FIG. 17 is a top view thereof;

FIG. 18 is a bottom view thereof; and,

FIG. 19 is an exploded front perspective view thereof.

The broken lines in the drawings are included for the purpose of illustrating environmental structure only and form no part of the claimed design.

1 Claim, 15 Drawing Sheets
